[57] CLAIM

The ornamental design for an article of jewellery, as shown.

DESCRIPTION

FIG. 1 is a perspective view of a pendant showing my new design;

FIG. 2 is a front elevational view;

FIG. 3 is a right side elevational view;

FIG. 4 is a left side elevational view;

FIG. 5 is a top plan view of the side;

FIG. 6 is a bottom plan view;

FIG. 7 is a perspective view of a finger ring showing a second embodiment of my new design;

FIG. 8 is a front elevational view of FIG. 7;

FIG. 9 is a right side elevational view of FIG. 7;

FIG. 10 is a left side elevational view of FIG. 7;

FIG. 11 is a top plan view of FIG. 7;

FIG. 12 is a bottom plan view of FIG. 7;

FIG. 13 is a perspective view of a earring showing a third embodiment of my new design;

FIG. 14 is a front elevational view of FIG. 13;

FIG. 15 is a right side elevational view of FIG. 13;

FIG. 16 is a left side elevational view of FIG. 13;

FIG. 17 is a top plan view of FIG. 13; and,

FIG. 18 is a bottom plan view of FIG. 13.

The broken line showing of an attachment means in FIGS. 1 through 18 is for illustrative purposes only and forms no part of the claimed design.
